Albert S. Newton

By *Knottis E. Bealove*
ATTORNEY

UNITED STATES PATENT OFFICE.

ALBERT S. NEWTON, OF PROVIDENCE, RHODE ISLAND.

WASTE-TRAP.

1,347,550.

Specification of Letters Patent. Patented July 27, 1920.

Application filed March 1, 1920. Serial No. 362,458.

To all whom it may concern:

Be it known that I, ALBERT S. NEWTON, a citizen of the United States, residing at Providence, in the county of Providence and State of Rhode Island, have invented 5 certain new and useful Improvements in Waste-Traps, of which the following is a specification.

My invention relates to waste traps. In 10 such traps a central vertical educt pipe is commonly used. Because of its tubular character the pipe in time develops, because of rust, holes whereby the seal of the trap is broken. In such traps also complete 15 accessibility to all interior portions of the trap for cleaning purposes is impossible.

The essential objects of my invention are to avoid the disadvantages of a vertical educt pipe; to prevent rust; to prevent holes 20 in the member occupying the place of the educt pipe whereby the seal of the trap is broken; to make the trap accessible in all portions for cleaning purposes; and to attain these ends in a simple, inexpensive and 25 efficient structure.

To the above ends essentially my invention consists in such parts and in such combinations of parts as fall within the scope of the appended claims.

30 In the accompanying drawings which form a part of this specification,

Figure 1 is a central vertical section of a trap embodying my invention, and

35 Fig. 2, a section of the same on line x, x , of Fig. 1.

Like reference characters indicate like parts throughout the views.

The trap comprises a substantially cylindrical tubular body or casing 5 having an 40 open top and bottom. Upon the upper and lower ends of the body are internal threads 8 and 9 respectively. An elbow 10 has threads 11 on one end engaging threads 8, and threads 12 on its outer end engaging 45 threads 13 on a pipe 14. The members 10 and 14 constitute the eduction pipe or outlet of the trap.

A removable member or cap closes the lower end of the trap. This comprises a

circular plate 17 adapted to abut against 50 the end of the trap, and an annular flange 18 inset from the periphery of the plate upon its rear face and provided with a thread 20 adapted to engage the thread 9. There is a squared projection 21 on the 55 exterior face of the plate to accommodate a wrench. The central portion of the plate has in its inner face a threaded recess 22 to receive a thread 24 upon a solid post 25 supporting upon its upper end a horizontally disposed baffle plate 26 having a depending peripheral portion 27.

The body has near its lower end an annular opening 29 provided with a thread 30 engaging a thread 31 on an upwardly directed elbow 32. A thread 34 in the upper end of the elbow engages a thread 36 on a vertical pipe 37. This pipe and elbow constitute the inlet pipe.

The course of the water is from the inlet 70 pipe into the body of the trap, and thence through the outlet pipe. The normal water level in the trap is some distance below the baffle plate.

It will be observed that the outlet is in the 75 upper portion of the body, and that the sole function of the post is to support the baffle plate. Hence the post is solid.

For interior cleaning the cap is by rotation removed carrying the post and baffle 80 plate, thus making the interior of the entire trap body wholly accessible.

The function of the baffle plate 27 is to intercept the passage of the water from the inlet pipe to the outlet pipe during the 85 period of siphonage. The water which impinges upon the bottom face of the baffle plate is thrown down into the body of the trap.

I claim:—

1. In a waste trap, a body, an inlet pipe near the bottom of the body, an outlet pipe in the upper portion of the body, a vertical post in the body, and a baffle plate on the top of the post below the outlet pipe. 90

2. In a waste trap, a body, an inlet pipe near the bottom of the body, an outlet pipe in the upper portion of the body, a solid 95

vertical post in the body, and a horizontally disposed baffle plate on the post between the inlet pipe and the outlet pipe.

3. In a waste trap, a body provided with a thread upon its lower end, a cap upon the body provided with a thread adapted to engage the first thread, a projection upon the outer face of the cap, a post fast to the

inner face of the cap, a baffle plate on the post, an outlet pipe in the body above the 10 baffle plate, and an inlet pipe in the body below the plate.

In testimony whereof I have affixed my signature.

ALBERT S. NEWTON.
